UNITED STATES PATENT OFFICE.

CHESTER O. HENDERSON, OF COLUMBUS, OHIO, ASSIGNOR TO HENDERSON TIRE & RUBBER CO., INC., OF COLUMBUS, OHIO.

DESIGN FOR A TIRE TREAD.

Application filed September 27, 1922. Serial No. 3,830. Term of patent 7 years.

To all whom it may concern:

Be it known that I, CHESTER O. HENDERSON, a citizen of the United States, residing at Columbus, in the county of Franklin and State of Ohio, have invented a new, original, and ornamental Design for Tire Tread, of which the following is a specification, reference being had to the accompanying drawing, forming a part thereof.

In the accompanying drawings:

Fig. 1 is a sectional perspective view of a portion of a tire having a tread embodying my design.

Fig. 2 is a developed plan view of a portion of the tire tread.

I claim:

The ornamental design for a tire tread, substantially as shown.

CHESTER O. HENDERSON.
